(57) **CLAIM**

The ornamental design for a scent fishing floater, as shown and described.

DESCRIPTION

FIG. 1 is an isometric view of an embodiment of a scent fishing floater in an environment of use showing my new design. The broken lines form no part of the claimed design. FIG. 2 is an exploded isometric view of the scent fishing floater of FIG. 1. The broken lines form no part of the claimed design.

FIG. 3 is a front elevation view of the scent fishing floater of FIG. 1. The broken lines form no part of the claimed design.

FIG. 4 is a rear elevation view of the scent fishing floater of FIG. 1. The broken lines form no part of the claimed design. FIG. 5 is a right elevation view of the scent fishing floater of FIG. 1. The broken lines form no part of the claimed design.

FIG. 6 is a left elevation view of the scent fishing floater of FIG. 1. The broken lines form no part of the claimed design. FIG. 7 is a top plan view of the scent fishing floater of FIG. 1; and,

FIG. 8 is a bottom plan view of the scent fishing floater of FIG. 1. The broken lines form no part of the claimed design.
